UNITED STATES PATENT OFFICE.

BENJAMIN WESLEY SHOLTY, OF DECATUR, INDIANA.

CABINET.

SPECIFICATION forming part of Letters Patent No. 739,730, dated September 22, 1903.

Application filed February 12, 1903. Serial No. 142,998. (No model.)

To all whom it may concern:

Be it known that I, BENJAMIN WESLEY SHOLTY, a citizen of the United States, and a resident of Decatur, in the county of Adams 5 and State of Indiana, have made certain new and useful Improvements in Cabinets, of which the following is a specification.

My invention is an improvement in copy-holders designed especially for use on type-writer cabinets; and the invention consists in certain novel constructions and combinations of parts, as will be hereinafter described and claimed.

In the drawings, Figure 1 is a perspective view of the cabinet closed as when not in use. Fig. 2 is a perspective view of the cabinet open for use, parts being broken away and others shown in section. Fig. 3 is a vertical longitudinal section of the upper portion of the cabinet on about line 33 of Fig. 4. Fig. 4 is a front elevation, part in section, of the upper portion of the cabinet, one of the side shelves or leaves being lowered and the other raised to position for use and supported by the bracket. Fig. 5 is a detail inverted perspective view of a portion of the cabinet, showing one of the shelves drawn forward to position for use and in which position it will be supported by the hinged spring-actuated bracket. Fig. 6 is a detail front elevation of the copy-holder. Fig. 7 is a detail sectional view illustrating the handle-knob for operating the copy-holder. Fig. 8 is a detail view of the pivoted prop for tilting the case, and Fig. 9 is a detail view of one of the socket-plates for use with the handle-knob shown in Fig. 7 or with the prop shown in Fig. 8.

The cabinet A is in general respects in the form of a case of drawers having the framing 40 B and the drawers C, which slide into and out of position for use in the ordinary manner. The cabinet is also provided near its top with a sliding board D, which slides in guides D' into and out of position for use, as will be understood from Figs. 1, 2, and 3. The board D has a handle D² at its outer end. I also provide the cabinet at its upper end and above the slide D with a sliding board E, which slides at E' in guides in the framing and has 45 at its outer end a handle E² and is provided at such end with the lateral extensions E³, which abut the frame, as shown in Fig. 1,

when the parts are closed. This top slide E carries the case F for covering the type-writing machine, such case being pivoted at F' 55 and being provided at its edge F², opposite the hinges F', with a copy-holder G, hinged at G', so it can be adjusted to the position shown in Fig. 3 when the case is closed and to the position shown in Fig. 2 when the case 60 is opened. To operate the holder G to its different positions, I provide a shaft H, having a crank-arm H', provided at its outer end with a pin H², entering a groove G² in one side of the copy-holder, so the swinging of the 65 arm H' will adjust the copy-holder from the position shown in Fig. 3 to that shown in Fig. 2, and vice versa. The shaft H journals at H³ in the side of the case F and is provided outside the said case with a handle-knob I, 70 which is movable longitudinally on the shaft and is keyed to the same, so it may turn the shaft and also be moved longitudinally to enable its adjustment into and out of locked position. On the case I secure opposite the 75 inner end of the knob I a socket-plate J, having sockets J', into suitable ones of which a stud I' on the inner end of the knob I may be adjusted to secure the said knob, and with it the shaft H³ and the copy-holder G, operated 80 thereby, in different adjustments. A spring K operates to hold the knob I, with its stud I', in the sockets J' of the plate J, and yet permits the knob to be moved outward to release the stud I' from the socket J. 85

The copy-holder G is provided with sliding extension-frames g g', which slide in suitable guides in the body of the copy-holder and may be adjusted to the closed position (shown in Fig. 6) or to project beyond the opposite edges 90 of the copy-holder, as shown in Fig. 2.

It sometimes becomes desirable to throw the copy-holder G forward, as indicated in Fig. 2. This may be accomplished by means of the prop L, (shown in Fig. 8 and in Fig. 2,) 95 the said prop being secured to the inner end of the handle-knob I', similar in construction to the knob I and having a pin or stud corresponding to the stud I' of the knob I, operating in connection with a socket-plate L², similar to 100 the socket-plate J. (Shown in Figs. 7 and 9 and before described.) By this construction the prop can be adjusted from the position shown in Fig. 1 to that shown in Fig. 2, in

which latter position it will project beyond the case F in such manner as to tilt the said case forward, as shown in Fig. 2 of the drawings.

5 On its opposite sides the cabinet is provided with shelves or leaves M, which when raised to the position shown in Figs. 1 and 5 and at the right in Fig. 4 stand in the same plane as the slide E, and when drawn forward, 10 as shown at the left in Fig. 2, alongside the slide E form lateral extensions of the top provided by the said slide, as desired. The shelves M are hinged to and slideable along the cabinet, being provided at their inner 15 edges with eyes M', which embrace and slide along and also turn upon rods N, secured to the frame of the cabinet, as best shown in Fig. 5, cushions O, of rubber or other suitable material, being provided to ease the jar or shock 20 of the brackets M when they are drawn forward to the position shown in Fig. 5 or pushed back to the position shown in Fig. 1, as will be understood from the drawings. For supporting the shelves when raised and drawn forward, 25 as shown in Fig. 5, I provide the brackets P, having their upright arms connected by a spring-hinge P' with the cabinet, so the said brackets will normally stand in against the side of the cabinet and beneath the projecting 30 ledges b of the framing at the sides of the cabinet, as shown at the left in Fig. 4, so the said brackets will not interfere with the shelf M hanging down, as shown in said Fig. 4. The horizontal arm P² of the bracket P has 35 its outer end connected by a chain P³ or other suitable connection with the shelf M, so the said shelf as it is drawn forward will draw the bracket against the connection of its spring P' out to the position shown in Fig. 5 40 and at the right in Fig. 4, in which position it will firmly support the shelf M, as desired. It will also be noticed that when the shelf is pushed back from the position shown in Fig. 5 to that shown in Fig. 1 the tension of the 45 connection P³ will be released and the spring P' will operate to throw the bracket back to the position shown at the left in Fig. 4, so the shelf M may hang as illustrated in the 50 said figure.

50 By the described construction it will be seen I provide a cabinet supplied with numerous drawers and above the same with a sliding board, which can be drawn out, as shown in Fig. 3, for use as a desk, and also 55 above the said slide D with a slide E, which in use carries the type-writing machine and the case therefor, the latter being provided with a copy-holder, which can be adjusted into and out of position for use, and with a 60 prop for tilting the case to bring the copy-holder nearer to the eye when desired, and also provide the cabinet with side shelves, which can be drawn forward to form lateral extensions of the top provided by the slide E and 65 will as they are so drawn forward automatically adjust their supporting-brackets into position to hold the said shelves up in posi-

tion for use, as is desired; such brackets being spring-actuated, so they will automatically turn out of the way of the shelves when 70 the latter are pushed back to the position shown in Fig. 1.

It will be noticed that the shelves or leaves cannot be pulled forward without first raising them to a horizontal position, as the 75 chains which connect said leaves with the swinging spring-actuated brackets will prevent the shelves from being pulled forward, except after they have been raised to a horizontal position, so they can swing the brackets out to position to support the shelves. The framing, the sliding board E, the sliding and swinging slides or leaves M, their brackets and co-operating devices are included in the subject-matter of a separate application 80 for patent, Serial No. 126,726, filed by me October 10, 1902.

Having thus described my invention, what I claim as new, and desire to secure by Letters Patent, is—

1. The combination substantially as herein described of the cabinet, the type-writer case hinged at one edge to the cabinet whereby it may be opened, adjusting devices adjacent to the top of the case for supporting the same 95 when opened, a copy-holder hinged at one edge to the front edge of the case and provided in one side with a groove, a shaft journaled to the case and having a crank-arm provided with a pin operating in the side groove 100 of the copy-holder, and a sliding extension-frame carried by the copy-holder and movable, when the case is opened, beyond the hinged edge of the copy-holder substantially as set forth.

2. The combination of a type-writer case hinged at its lower rear edge, an adjustable support adjacent to the top of the case at the rear side thereof whereby to form a support for the case when the latter is opened, a copy-holder hinged to the case adjacent to the lower front edge thereof and means carried by the case for swinging the copy-holder into position for use when the case is opened substantially as set forth.

3. The combination substantially as herein described, of the support, the type-writer case hinged at its lower rear edge to the support, adjustable devices on the case at the upper rear edge thereof, whereby the case may be propped up on the support when such case is opened, a copy-holder adjustably supported at the lower front edge of the case, and means for operating said copy-holder, substantially as set forth.

4. The combination with the case of the copy-holder hinged thereto and provided with a longitudinal groove, a shaft having a crank-arm provided with the pin operating in said groove, and devices for operating said shaft 130 and for locking the same in different adjustments, substantially as set forth.

5. The combination of the case, the copy-holder hinged at one edge to the case, the

shaft journaled in the case, and having within such case a crank-arm engaged with and operating the copy-holder, the knob for operating the shaft, and detent devices for holding the knob when adjusted to different positions, substantially as set forth.

6. The combination of the support, the type-writer case hinged at its lower rear edge to the support, and adjustable devices on the case at the upper rear edge thereof whereby the case may be propped up on the support when opened.

7. The combination substantially as described of the support, a type-writer case hinged at its lower rear edge to the support, a copy-holder carried by the case at the lower front edge thereof, and devices on the case at the upper rear edge thereof whereby the case may be tilted up on the support when such case is opened.
